ATTORNEYS

UNITED STATES PATENT OFFICE.

JESSE McCOMAS, OF LOS ANGELES, CALIFORNIA.

TELEPHONE ATTACHMENT.

Application filed December 12, 1922. Serial No. 606,546.

To all whom it may concern:

Be it known that I, JESSE McCOMAS, a citizen of the United States, residing at Los Angeles, in the county of Los Angeles and State of California, have invented new and useful Improvements in Telephone Attachments, of which the following is a specification.

This invention relates to telephone attachments and has for its object to provide a combined sanitary cover, memoranda pad and advertising device.

Another object of the present invention is to provide a device of such construction and character that it may be readily applied to the transmitter of a telephone set in such manner that the mouth piece of the telephone is not only protected from direct contact with the breath of users of the telephone but furthermore the mouth piece is so comparatively covered that it is protected against damage in the event that the telephone is knocked over or falls. The device also forms a protector in that it prevents the telephone from being lifted by the mouth piece as a purchase portion.

A further object of the invention is to provide a sanitary cover of such character and arrangement that while it prevents the blowing of the breath directly onto the mouth piece, it does not in any wise interfere with the efficiency of telephonic conversation and on the contrary is found to enhance the efficiency.

The device has also for its object to provide for a very compact, ornate and effective advertising and memoranda means.

Other objects and advantages will be made manifest in the following specification of an embodiment of the invention illustrated in the accompanying drawings, wherein:

Figure 1 is a perspective of the device.

Fig. 2 is a side elevation of the device as applied to the transmitter of a telephone.

Fig. 3 is a longitudinal section of the device.

Fig. 4 is a detail, sectional view showing the trunnion lug receiving a roll of paper.

An object of the invention is to provide a combined sanitary cover, memoranda pad and advertising device of substantial and inexpensive construction and to provide a

device consisting of substantially one integral element upon which may be readily mounted and removed a memoranda receiving and mouth piece covering web.

The device is shown as comprising a unitary structure having a socket plate or back panel 2 which is perforated at 3 to pass over the usual threaded reduced end of the mouth piece P of a telephone set so that when the back panel 2 is disposed in front of the transmitter and the mouth piece screwed thereon the mouth piece will serve to clamp the back panel in place between the transmitter shell and the mouth piece. The upper portion of the back panel 2 is provided with a forwardly and upwardly inclined bracket 4, the parallel edges of which are provided with bearing lugs or tongues 5, the upper ends of which are designed to provide pivots upon which may be rotatively supported a roll of material such, for instance, as a web of paper W which has, preferably, a width slightly greater than the diameter of the mouth piece P so that the web W, when pulled down across the front of the mouth piece, will substantially cover the same and, therefore, prevent the breath from being blown onto the mouth piece when the telephone is in use.

The top bracket 4 has a transverse slot 6 through which the leading end of the paper web can be threaded to pass down in front of the mouth piece and the front upper end of the bracket 4 is provided with an upstanding plate or leaf 7 disposed in front of the roll W which is mounted on the pivot portions 5' in the bearing lugs 5. The pivot portions may and, preferably, do consist of inwardly pressed protuberances to enter the core C of the roll of web W.

The upwardly extending plate or leaf 7 forms a cover and protector for the front of the roll of web and upon the face of this leaf there may be placed any desired legend, data or, preferably, advertising matter indicated at A, so that the device may serve effectively when applied to the telephone as an advertising medium.

From the lower portion of the back panel or mounting plate 2 there extends forwardly and downwardly a bottom plate 10 and from the outer portion of this there is turned downwardly a platen or table forming sec-

tion 11 of suitable width and length so as to conveniently support the contiguous portion or section of the web W which is pulled downwardly across the mouth piece P. To 5 provide for the proper guiding and holding of the sanitary and memoranda web W, a guide loop or bar 12 is punched up from the material sufficiently to permit the passage of the web downwardly across the face of 10 the writing table 11. The lower end of the table is also provided with a transverse aperture 13 and the lower marginal portion of the table 11 is slightly struck up in a transverse bar 14 so that the web W can be 15 readily pulled down from the roll by a pressure of the thumb or a finger on the face of the web between the upper and lower transverse guide bars 12 and 14.

It will be seen that the device is in its 20 preferred form made of one integral piece of inexpensive and substantial sheet metal wholly devoid of separable or moving parts and, therefore, of practicable and substantial form.

25 I provide by this invention not only a sanitary and removable antiseptic web W but this web further is serviceable as a memoranda keeping means since it provides for the making of notes on the section there- 30 of successively exposed on the writing table 11 between the guide and holding bars 12-14.

After a memorandum has been entered on 35 the portion of the web resting over the table 11, the web can be pulled down as by pressure on the web downwardly on the table 11 and after a sufficient portion has been projected beyond the guide bar 14, the end 40 of the web is then grasped and by a quick movement the exposed section is severed along the lower edge of the guide bar 14.

For convenience, a writing instrument as 45 a lead pencil L can be connected as by a chain or other flexible means 15 to the device so that it may be constantly in position for instant use when necessary in making memoranda.

It is to be understood that if desired the 50 web may be provided with a continuous form of advertising or other matter, or the advertising may be printed in the form of spaced cards, or notices, or paragraphs, or advertising or other pictures may be applied thus giving the web the further function 55 of being an advertising or other useful medium as well as for covering the mouth piece and forming a memoranda sheet.

Further embodiments, modifications and 60 variations may be resorted to within the spirit of the invention as here claimed.

What is claimed is:

1. A one-piece device attachable to a telephone transmitter and consisting of a back plate perforated to receive the usual threaded shank of the mouth piece of a 65 transmitter and adapted to be secured to the transmitter shell by said mouth piece, a web roll supporting bracket at the top of the plate, and a table part for supporting the web to enable the writing of memoranda on the extended portion of the web, said table part having upper and lower guide loops for the web.

2. A one-piece device attachable to a telephone transmitter and consisting of a back plate perforated to receive the usual threaded shank of the mouth piece of a 70 transmitter and adapted to be secured to the transmitter shell by said mouth piece, a top bracket having web roll supporting lugs, 75 said bracket having an eye for the web, a web guiding and retaining means to which the web is extended from the roll supporting means and across the mouth piece so that the web covers the mouth piece, and a roll covering element having a front face 80 adapted to receive an advertising medium.

3. A one-piece device applicable to a telephone transmitter and consisting of a plate with a perforated attaching part having an 85 upwardly and forwardly extending web roll supporting portion and which is perforated to form a guide for the web drawn from the roll, a downwardly and forwardly extending portion having a transverse 90 guide for the withdrawn web, said part having an integral leaf forming a table portion having a lower guide and retaining device for the web, whereby the web as it is 95 unwound from the roll will extend in a covering position across the mouth piece and will be supported for memoranda purposes on the said table.

4. A combined sanitary and memoranda sheet holder and guide, for attachment to a telephone transmitter, comprising a sheet metal structure having a back plate perforated to receive the mouthpiece shank, a top bracket having bearing lugs for a sheet roll and having a transverse slot in its front portion to receive the unwound sheet, and a bottom plate having at its front a down-turned table, said table having upwardly punched cross-loops forming retaining guides for the sheet as it is drawn from 100 covering position over the mouthpiece.

In testimony whereof I have signed my name to this specification.

JESSE McCOMAS.
